UNITED STATES PATENT OFFICE.

IRA H. SPENCER, OF HARTFORD, CONNECTICUT, ASSIGNOR TO THE ORGAN POWER COMPANY, OF HARTFORD, CONNECTICUT, A CORPORATION OF CONNECTICUT.

BLOWER FOR MUSICAL INSTRUMENTS.

No. 835,570.

Specification of Letters Patent.

Patented Nov. 18, 1906.

Application filed April 3, 1905. Serial No. 253,609.

To all whom it may concern:

Be it known that I, IRA H. SPENCER, a citizen of the United States, and a resident of Hartford, in the county of Hartford and State of Connecticut, have invented a new and Improved Blower for Musical Instruments, of which the following is a specification.

My invention relates to the class of devices for producing a current of air, the improved device forming the subject-matter of this application being more especially applicable for creating a current for use in musical instruments, although it may be found applicable for use in connection with other devices and is therefore not limited especially to use in connection with a musical instrument.

The object of my invention is to provide a blower that shall be free from the objections present in prior devices resulting from the noise created in the operation of the blower; and a further object is to provide a device which may be set up or installed with comparative readiness and ease; and a further object of the invention is to provide a device having the advantages hereinbefore noted and in which access to the motor may be gained without disturbing the air-pressure.

One form of device in the use of which these objects may be attained is illustrated in the accompanying drawings, in which—

Figure 1 is a view in central vertical longitudinal section of a blower embodying my invention. Fig. 2 is a view in crosswise section through the device shown in Fig. 1 on a plane passing through the delivery-pipe and looking toward the right. Fig. 3 is a view in crosswise section through the device shown in Fig. 1 on a plane passing through the structure between the dividing-walls and a fan-disk, looking toward the left, and with the upper part of the fan-disk broken away. Fig. 4 is a detail view showing the bearing for one end of the shaft.

In the accompanying drawings the numeral 1 denotes an outer case, and 2 an inner case. These casings are preferably formed of sheet metal and are supported by rings 3, which may be formed integral with either of the casings or secured thereto in any convenient manner.

In constructing casings for blowers for musical instruments prior to my invention it has been common practice to divide the casing longitudinally; but an objection is present in such a construction from the fact that the current of air generated by the fans and flowing circumferentially around the casing and across the seam formed by the joint create considerable noise. It is desirable in devices of this class that all noise shall be prevented. I have found by repeated experiments that when the casing is divided circumferentially instead of longitudinally that this noise is prevented. I therefore form the casing in sections divided circumferentially, as shown in Fig. 1 of the drawings, and interpose a sound-insulating material 4 between the outer and inner casings. Heads 5 6 are provided at each end of the casing, these heads being secured together and to the casing and the sections of the casing being secured together, as by means of rods 7 passing through the heads and along the outer surface of the casing 1 and secured, as by means of thumb-screws 8, fixed to the screw-threaded ends of the rods. Dowel-pins 9 are secured to the rings 3 for the purpose of holding them in alinement. The head 5 is provided with a cover 10, hinged at 11 to the support 12 and secured, as by a thumb-screw 13. The head 6 is provided with a cross-bar 14, forming a bearing for one end of the shaft 15, an opening 16 being formed through the head for the admission of air. Supports 17 are provided for sustaining the blower as a whole.

A main division-wall 18 extends across the casing, dividing the motor-chamber 19 from the air-compartments 20. This main division-wall has an opening 21, closed by a cap 22. This cap is loosely supported on the shaft 15 and has a lining 23 of felt on that face next to the wall 18. It is loosely supported and is held in place by the air-pressure within the air-chamber. Thus it forms what might well be termed a "floating bushing" covering the opening 21 between the motor-chamber 19 and air-compartments 20, always adjusting itself with the shaft without liability of cramping or binding.

A motor 24 is located in the motor-chamber 19 and is connected with the shaft 15 by

a universal joint 25. This shaft is supported at one end in the bar 14 in a universal bearing 26.

In setting up the casing it often happens that the motor will be moved to some extent, and thus the shafting will be thrown out of alinement. This is especially the case in a structure of the kind herein shown and described, which is comparatively light and must be of such character which is required by the uses to which it is to be put. By constructing the universal bearing as shown in Fig. 1 of the drawings it will be seen that the shaft will readily accommodate itself to the position of the motor and that the latter may be moved to a considerable extent without interfering with the proper operation of the shaft, and hence when the blower is once set up it need not be taken down by reason of the motor having been moved from its proper position with the shaft in alinement.

Partitions 27 divide the air-chamber up into compartments 20, in which are located fan-disks 28, to which are secured fans or vanes 29. The edges of the fans revolve in close proximity to the partitions 27, the air passing through the openings 30 in these partitions.

Shields 31 are located in the air-compartments in any desired number, these being clearly shown in Fig. 3 of the drawings. An outlet 32 leads from the inner air-compartment, this outlet or pipe being located in a line tangential to the wall of the circular air-compartment.

The air enters through the opening in the cover 6 at each side of the cross-bar 14 and passes into each of the succeeding chambers, the pressure being raised in each of the succeeding chambers. The shields 31 prevent a circular motion of the air in all of the air-compartments except the innermost, and in this chamber circular motion is allowed, and owing to the location of the outlet-pipe the air freely passes out of said pipe to a suitable reservoir or pressure-chamber or direct to the musical instrument, as the case may be.

The air in each of the succeeding compartments from the inlet 16 is raised in pressure, being higher than in the next preceding compartment. I have shown herein the outlet 32, extending from the innermost compartment; but it will be obvious that outlets may be made from any of the compartments and air supplied in this way under different pressures, as may be required, from the same blower.

What I claim as my invention, and desire to secure by Letters Patent, is—

1. In a blower for musical instruments or the like, including a casing composed of sections having inner and outer concentric tubes, means for holding the sections in engagement, covers for each end of the casing, a motor located within the casing, a shaft

connected with the motor, and fans mounted on the shaft and within the casing.

2. In a blower for musical instruments or the like, a casing having a motor-chamber and compartments for air under pressure and divided from the motor-chamber, a shaft extending from the motor into the air-compartments, a floating self-adjusting bushing intermediate the motor and air-compartments, and fans secured to said shaft and located within the air-compartments.

3. In a blower for musical instruments or the like, a casing composed of inner and outer concentric tube-sections with means for holding said sections in alinement; a motor located within said casing, a shaft connected with the motor and supported at its opposite end in a universal bearing, said bearing supported in the casing, and fans secured to said shaft.

4. In a blower for musical instruments or the like, a casing composed of inner and outer concentric tube-sections with means for holding said sections in alinement, a motor secured therein, a motor-shaft, a shaft supported at one end in a universal bearing, said bearing supported in the casing, a universal joint connecting said shaft with the motor-shaft, and fans secured to said shaft.

5. In a blower for musical instruments, or the like, a blower-casing having a motor-chamber and air-compartments, a motor located within the motor-chamber, a motor-shaft, a shaft extending from the motor-shaft through the air-compartments, supported at its outer end in the motor-casing and connected with said motor-shaft, a floating disk supported on the shaft and closing the opening between the motor-chamber and air-compartments, and fans secured to said shaft.

6. In a blower for musical instruments or the like, a shell having a motor-chamber and air-compartments, a motor located within the motor-chamber, a shaft connected with the motor by a universal joint and supported at its opposite end in a universal bearing, a floating self-adjusting cap supported by the shaft to close the opening through which the shaft extends from the motor-chamber, an outlet extending tangentially from the wall of the innermost air-compartment, and fans secured to the shaft and located in each of the compartments.

7. In a blower for musical instruments or the like, a casing divided into a number of air-compartments, a motor located within the casing and having a shaft extending through said air-compartments, fans located in each of the compartments, and an outlet from a number of said compartments whereby air under different pressures may be obtained from said shell.

8. In a blower for musical instruments or

the like, a shell formed in sections divided circumferentially and separated into a number of air-compartments and a motor-chamber, a motor located within said chamber, a shaft flexibly connected with the motor and extending through the air-compartments, a floating self-adjusting cap for closing the opening from an air-compartment into the motor-chamber, fans secured to said shaft and lo-

cated in each of the air-compartments, and outlets from a number of said chambers whereby air under different pressures may be obtained from said shell.
